UNITED STATES PATENT OFFICE.

PAUL S. MILLICE, OF HAMILTON, OHIO, ASSIGNOR TO HERRING-HALL-MARVIN SAFE COMPANY, OF NEW YORK, N. Y., A CORPORATION OF NEW YORK.

SAFE.

1,404,043.

Specification of Letters Patent. Patented Jan. 17, 1922.

Application filed July 19, 1920. Serial No. 397,287.

To all whom it may concern:

Be it known that I, PAUL S. MILLICE, a citizen of the United States, residing at Hamilton, in the county of Butler and State 5 of Ohio, have invented certain new and useful Improvements in Safes, of which the following is a specification.

My invention relates to safes, and has for its object the provision of novel means for 10 enhancing the fire-resisting qualities of a safe.

I have found that one of the great considerations for enhancing the fire-resisting qualities of a safe is to prevent passage of 15 gases, oxygen or air, or a circulation, through the joints at the door or doors of the safe. Attempts have heretofore been made to accomplish this purpose, but these have been found wanting when the safe has been subjected to comparatively severe tests or fires. 20 By means of my invention the fire-resisting qualities of a safe are very materially enhanced, as has been demonstrated by very severe tests.

25 It is the object of my invention to provide a safe with novel means for closing the joint between the wall of the door-opening and the door, whereby to enhance the fire-resisting properties of the safe; further, to provide 30 a safe with novel means of the character mentioned at the joint so constructed and arranged that the passage of air, oxygen or gases past the joint, or circulation through the joint, while subjected to the heat of a 35 fire, is substantially prevented; further, to provide novel means so arranged that warping of metal during the course of a fire will tend to exert pressure between complementary faces in the joint to cause more intimate 40 closing of the joint between said faces; and, further, to provide a safe with coengaging lapping wedge-walls in the joint.

The invention will be further readily understood from the following description and 45 claims, and from the drawings, in which latter:

Fig. 1 is a horizontal section of a safe embodying my invention, taken in the plane of the line 1—1 of Fig. 2.

50 Fig. 2 is a vertical section of the same, taken in the plane of the line 2—2 of Fig. 1.

Fig. 3 is a vertical cross-section of the same, taken in the plane of the line 3—3 of Fig. 1; and,

55 Fig. 4 is a horizontal section of a safe em-

bodying my invention and having a single door.

I herein show and describe an exemplification of my invention, and herein broadly claim my invention. I have in another application for patent, Serial No. 397,288, filed July 19, 1920, copending with this application, shown, described and claimed a further adaptation of my invention.

The body of the safe is shown at 21, as 65 comprising an inner wall 22 and an outer wall 23, preferably of sheet-metal, forming a cavity between said inner and outer walls, for instance at the sides, top, bottom and back of the safe, in which suitable fire-resisting material may be located in suitable manner. This cavity is shown as containing a fire-resisting body 25 of suitable composition. Suitable re-enforce angle-plates, which may be of sheet-steel, are shown at 70 26, at the corners of the body.

Referring to Figs. 1, 2 and 3, which show a double-door safe, the doors are represented at 27 and 28, respectively hinged to the body by hinges 29, 30, the pivot-pins of which are 80 shown at 31, 32.

Each of the doors comprises a front wall 35, a rear wall 36, and an edge or marginal wall 37 surrounding the door, to form a cavity in the door, in which a suitable fire-resisting body 38 is placed, as desired, preferably to provide a bolt-work and lock space 39.

The door-opening is shown at 41. The wall 42 of the door-opening, and the marginal wall 37 of the door, are provided with complementary fire-resisting means. An exemplification of my invention is shown, which may be selectively located at the hinge edge of the door, at the swinging edge of the door, at the top of the door, at the bottom of the door, or between the doors, or at all of said locations, so as to surround the door, as may be desired.

Thus the wall of the door-opening is exemplified of sheet-metal, for instance, sheet-steel, and is shown formed with forwardly projecting wedge-like rib 46 and a rearwardly projecting wedge-shaped groove 47. The marginal wall of the door coacting 100 with the marginal wall of the door-opening is provided with a rearwardly projecting wedge-like rib 48 and a wedge-shaped groove 49. The rearwardly projecting wedge-like rib 48 coacts with the forwardly 105 110

projecting wedge-like rib 46 of the wall of the door-opening. The wall of the door-opening and the margin of the door have complementary faces which coact with pressure between them to form a tight joint between the margin of the door and the wall of the door-opening when the door is closed. Complementary inclined faces are provided respectively for the margin of the door and 10 the wall of the door-opening which form a seal when the door is closed.

The complementary coacting faces preferably extend slantingly with relation to the plane of the door when the door is closed, 15 and are preferably located at an acute angle in an acute angle to said plane, and preferably slant forwardly toward the middle of the door when the door is closed.

The complementary coacting faces preferably exert lateral pressure upon one another for instance in the general direction of the plane of the door, to form a close joint, when the door is closed, the pressure exerted by the face on the door being preferably in a direction toward the middle portion of the door, so as to normally urge the wall of the door-opening toward the door when the door is closed.

In the present exemplification the wall 30 of the door-opening is provided with a front laterally outwardly extending flange 51, fixedly secured to the front wing of the front angle-plate 26, as by rivets or welding, with a filler-strip 50 between the flange 35 and plate. At the inner edge of this flange, the sheet metal of the wall of the door-opening is bent rearwardly to form a rearwardly and inwardly slanting portion 52, at the rear end of which latter there is a 40 forward lateral inward bend to form a portion 53, which coacts with the portion 52 to form the wedge-groove 47. At the forward end of said portion 53, the sheet-metal is provided with a bend to form a 45 rearwardly and laterally and inwardly extending portion 54 which, with the portion 53, forms the wedge-like rib 46.

At the rear end of the portion 54 the wall of the door-opening is provided with 50 a bend to form a shoulder 55 and a laterally outwardly extending portion 56. At the outer edge of the latter the wall is provided with a rearward bend to form a rearwardly extending portion 57. The rear edge of the 55 latter, is provided with an inward bend to form a laterally inwardly extending flange 58. The rearwardly extending portion 57 is preferably fixedly secured, as by welding, to the inner wall of the body of the 60 safe, and the side-wall 59 of the cabinet-work for the interior of the safe is located in rear of the flange 58, when employed.

The margin of the door is preferably also of sheet-metal, for instance, sheet-steel. It 65 is exemplified as having a front laterally

and inwardly extending flange 61, at the outer edge of which there is a bend to form a rearwardly and inwardly slanting portion 62, at the rear end of which there is a bend to form a forwardly and inwardly laterally slanting portion 63, to form the wedge-like rearwardly projecting rib 48. At the front edge of the latter there is a rearward bend to form a rearwardly laterally and inwardly projecting portion 64, 75 which coacts with the portion 63 to form the wedge-shaped groove 49.

At the rear edge of the portion 64 there is a lateral inward bend to form a laterally inwardly extending portion 65, at the inner edge of which there is a bend to form a rearwardly extending portion 66, at the rear end of which latter there is a lateral inwardly extending flange 67, to which the rear plate 36 of the door may be suitably secured, as by screws 68. The portions 65 and 66 form a recess in which the ends of the bolts are normally located when the bolts are withdrawn for opening the door.

The wall of the door-opening and the 90 margin of the door are preferably formed up out of sheet-steel by pressing or other suitable method.

The front wall 35 of the door preferably laps the front end of the joint between the 95 door and wall of the door-opening at the hinge-edge of the door, as shown at 71.

The front wall of the door is suitably rigidly secured to the flanges 61, as by rivets or welding, and the flanges 51 are suitably 100 rigidly secured to the sheet-metal filler-strip 50 and the front flanges of the angle-plates 26, as by rivets or welding.

When a safe is provided with a double door, one of the doors is, in the present exemplification, at the joint between the doors, formed similarly to the wall of the door-opening, the parts being indicated by similar but primed reference numerals, except that the flange 58' is turned the reverse way 105 to project toward the middle portion of the door. The portions 56' and 57' form a recess in which the ends of the bolts between the doors are normally located when the bolts are withdrawn for opening the doors. 110

Coacting faces are formed at the joint between the doors which coact similarly to the faces 53, 63, and preferably act with lateral pressure to form a close joint between the doors, and act to hold the doors toward each 120 other when the doors are closed.

When a safe is provided with a single door, exemplified at 70, (see Fig. 4), the construction of the wall of the door-opening and of the margin of the door, at the swinging end of the door, may be similar to the structures described with reference to the double-door safe.

Suitable means are provided for holding the door or doors in closed relation. Thus, 130

bolts 74, 75, 76, 77, 78 and 79, are provided to coact with the shoulders 55 of the wall of the door-opening, the ends of the bolts co-acting with the shoulders being provided with inclined faces 81 coacting with said shoulders to draw the doors inwardly, whereby lateral pressure in the direction of the plane of the door is caused between the complementary inclined faces between the door and the wall of the door-opening. Bolts 82, also having inclined wedge-faces 81, act between the doors when double doors are employed. Suitable operating means and locking means are provided for the bolts, not more particularly described because well-known.

Experience has shown that when a safe is subjected to the intense heat of a fire, there is a tendency of the walls of the door-opening to spread and to separate from the door, thereby forming a passage for gases, or circulation, at the joint between the wall of the door-opening and the margin of the door. This tendency is resisted in my invention, in which the forwardly projecting face 53 is received to the inside of the rearwardly projecting face 63, preferably with pressure tending to increase pressure between said complementary faces so as to more firmly close the joint between the wall of the door-opening and the door. When a double door is employed there is a similar action at the joint between the doors when employing my invention.

In my improved construction the forwardly and inwardly slanting sheet-metal walls, or faces of the body, have the rearwardly and outwardly slanting walls, or faces, of the door, received to outside of the same to act as a wedge-structure to hold the safe-wall toward the door and prevent spreading or warping of said wall from the door. The wedge-wall of the door seats upon the wedge-wall of the body regardless of variations in the relation of the hinge to the wedge-wall or the distance between wedge-walls, the construction readily accommodating itself to such variations as there may be in manufacture. A seating of the wedge-wall of the door upon the wedge-wall of the body is assured, the door moving inwardly to greater or less extent to insure such seating, there being sufficient space between the ends of the ribs and the bottoms of the grooves and between the reversely slanting faces to permit such selective movements of the door. The space 84 between the lip 71 of the door and the wall of the door-opening further permits such movements.

Having thus fully described my invention, what I claim as new, and desire to secure by Letters Patent, is:

1. A fire-resisting safe comprising a body and a door, and complementary sheet-strips

respectively of said body and of said door located in the plane of the door with said sheet-strip of said body located inwardly of and in interfering relation to said sheet-strip of said door, and arranged whereby pressure is caused between them in the general direction of said plane when the door is closed to form a fire-resisting joint.

2. In combination, a fire-resisting safe comprising a body having a door-opening provided with a wall, and a door having a margin, opposite sides of said wall provided with forwardly projecting slanting faces having space in front of them, opposite margins of said door provided with rearwardly projecting slanting faces having space in rear of them and received outside said forwardly projecting slanting faces of said wall, and arranged whereby closing movement of said door causes lateral pressure in the general direction of the plane of said door between said slanting faces and said closing movement is arrested by the wedge-action of said faces.

3. In combination, in a fire-resisting safe, a door comprising a sheet-metal margin formed with a rearwardly projecting wedge-rib formed of reversely bent portions of sheet-metal having a single angle therebetween, a sheet-metal wall coacting with said door, said sheet-metal formed with a forwardly projecting wedge-rib formed of reversely bent portions of sheet-metal having a single angle therebetween complementary to said first-named rib, said second-named rib located farther toward the middle of said door than said first-named rib when said door is closed, and means for mounting said door whereby the juxtaposed side-faces of said ribs when said door is closed have pressure between them and the apices of said respective wedge-ribs are spaced from the bases of their complementary ribs.

4. In a fire-resisting safe, the combination of a door having a sheet-metal margin formed with a rearwardly projecting rib and a rearwardly opening groove nearer the middle of said door than said rib, a sheet-metal wall for said door formed with a forwardly projecting rib and a forwardly opening groove farther from the middle of said door when said door is closed than said second-named rib, the inner face of said first-named rib located across the outer face of said second-named rib in said respective grooves when said door is closed, and means for said door to cause pressure between said faces and spacing between said respective ribs and the respective opposite walls of said grooves when said door is closed.

5. In a fire-resisting safe, the combination of a door and a jamb-wall therefor, the margin of said door and said wall having coacting pressure sections between them located substantially parallel with one of the sides

of an acute angle intersecting the front face of said door and projecting laterally outside and rearwardly of said door, said coacting pressure sections being continued in similar 5 angular directions beyond their normal coacting pressure portions to provide continued wedge-pressure relation between said faces.

6. In a fire-resisting safe, the combination 10 of a door and a jamb-wall therefor, the margin of said door and said wall having coacting pressure sections between them located substantially parallel with one of the sides of an acute angle intersecting the front face 15 of said door and projected laterally outside and rearwardly of said door, and means whereby to cause lateral pressure between said sections by rearward movement of said door, said coacting pressure sections being 20 continued in said acute angle beyond their normal coacting pressure portions to cause limit of rearward movement of the door solely by the wedging action of the door upon the jamb-wall of said coacting pressure 25 sections.

7. In a fire-resisting safe, the combination of a door comprising a sheet-metal margin, a sheet-metal wall with which said margin cooperates when said door is closed, said 30 sheet-metal wall having a forwardly projecting rib and a groove at the outer face of said rib formed up therein by reversely bending portions of said sheet-metal of said wall, said sheet-metal margin of said door 35 having a rearwardly projecting rib and a groove at the inner face of said last-named rib formed up therein by reversely bending portions of said sheet-metal of said margin, said ribs being wedge-formed at said faces, 40 and hanging means for said door, constructed and arranged whereby to exert lateral pressure between said inner face and said outer face when said door is closed.

8. In a fire-resisting safe, the combination 45 of a door comprising a sheet-metal margin, a sheet-metal wall with which said margin cooperates when said door is closed, said sheet-metal wall having a forwardly projecting rib and a groove at the outer face of 50 said rib formed up therein by reversely bending portions of said sheet-metal of said wall, said sheet-metal margin of said door having a rearwardly projecting rib and a groove at the inner face of said last-named 55 rib formed up therein by reversely bending portions of said sheet-metal of said margin, said ribs being wedge-formed at said faces, and hanging means for said door, constructed and arranged whereby to exert lateral 60 pressure between said inner face and said outer face, with the opposite faces of said grooves and ribs spaced from each other and the apices of said wedge-formed ribs distanced from the bottoms of said grooves 65 in which they are respectively received when

said door is closed and said lateral pressure between said faces is exerted.

9. In a fire-resisting safe, the combination of a door comprising a sheet-metal margin, and a sheet-metal wall with which said margin cooperates when said door is closed, 70 said sheet-metal wall having a groove formed up therein and said sheet-metal margin having a rib formed up therein received in said groove when said door is closed, with the median portion of said groove distanced farther from the middle of said door than the median portion of said rib when said door is closed, to cause lateral pressure between the inner faces of 75 said groove and said rib when said door is closed.

10. In a fire-resisting safe, the combination of a door comprising opposite sheet-metal margins, a body comprising opposite 80 sheet-metal jamb-walls of a door-opening with which said opposite margins cooperate when said door is closed, said opposite sheet-metal jamb-walls each having a groove formed up therein and said opposite sheet- 85 metal margins each having a rib formed up therein, and hinging means for said door, said respective ribs received in said respective grooves when said door is closed, with the median portions of said grooves distanced farther from each other than the distance between the apices of said ribs when said door is closed, to cause lateral pressure between the inner faces of said respective 90 ribs and grooves when said door is closed. 100

11. In a fire-resisting safe, the combination of a door comprising opposite sheet-metal marginal walls at opposite margins thereof, a body comprising a door-opening having opposite jamb-walls with which said opposite marginal walls respectively cooperate when said door is closed, each of said sheet-metal jamb-walls having a wedge-groove formed up therein and said sheet-metal marginal walls each having a wedge-rib formed up therein, and hinging means for said door, said respective ribs received in said respective grooves when said door is closed with the bottoms of said grooves spaced farther apart than the distance between the apices of said wedge-ribs when said door is in closed relation, to cause lateral pressure between the respective inner faces of said wedge-ribs and the respective inner walls of said grooves when said door 110 is closed. 115

12. In a fire-resisting safe, the combination of a door comprising a sheet-metal margin formed up with a sheet-metal wedge-rib and a wedge-groove at the inner 120 face of said rib, a sheet-metal complementary wall formed up with a sheet-metal wedge-rib and a wedge-groove at the outer face of said second-named rib, and hinging means for said door, said ribs located in said 125 130

grooves with the apex of each of said ribs located intermediate between the base and the apex of its opposing wedge-rib and with lateral pressure between said faces to press 5 said faces toward each other respectively in directions away from the opposite faces of said grooves when said door is closed.

13. In a fire-resisting safe, the combination of a door comprising a sheet-metal margin formed up with a sheet-metal wedge-rib and a wedge-groove at the inner face of said rib, a sheet-metal complementary wall formed up with a sheet-metal wedge-rib and a wedge-groove at the outer face 10 of said second-named rib, and hinging means for said door, said ribs located in said grooves with the apex of each of said ribs spaced from the bottom of the groove in which it is received, with lateral pressure 15 between said faces and with said ribs spaced from the opposite faces of said grooves when said door is closed.

14. In a fire-resisting safe, the combination of a door comprising a sheet-metal margin formed up with a sheet-metal wedge-rib and a wedge-groove at the inner face of said rib, a safe-body comprising a jamb-wall of a door-opening formed up with a sheet-metal wedge-rib and a wedge- 20 groove at the outer face of said second-named rib to form a door-joint between said door and said body, said door provided with a front flange received across said joint, said flange normally spaced from the portion of said body in rear thereof when the 25 door is closed, hinging means for said door,

and closing means for said door comprising clamping bolts to press said inner face of said first-named rib upon said outer face of said second-named rib with the apices of 40 said ribs spaced from the bottoms of their receiving grooves when said door is closed.

15. In a fire-resisting safe, the combination of a door having a plurality of edges, a body, hinge-mechanism between said door 45 and said body, and a wall having a plurality of sides, said sides respectively provided with forwardly projecting ribs and grooves outside said ribs, said edges provided with a plurality of rearwardly projecting ribs and rearwardly opening grooves inside said last-named ribs, said second-named ribs received outside said first-named ribs, said ribs having complementary wedge-faces, said wedge-faces of said door movable cross-wise of said wedge-faces of said body, with said respective ribs received in 50 said respective grooves with the apices of said ribs spaced from the bottoms of said grooves when said door is closed, and the 55 relations of said wedge-faces and said hinge-mechanism being such as to cause full wedge seating of said door-ribs on said wall-ribs to prevent seating of said ribs in the bottoms of said grooves. 60 65

In testimony whereof, I have hereunto signed my name in the presence of two subscribing witnesses.

PAUL S. MILLICE.

In presence of—

RALPH L. HINDS,
DELMO WERNING.
